UNITED STATES PATENT OFFICE.

DANIEL SEBRING, OF SPOKANE, WASHINGTON.

SAW-GAGE.

1,153,262.

Specification of Letters Patent. Patented Sept. 14, 1915.

Application filed July 29, 1914. Serial No. 853,849.

To all whom it may concern:

Be it known that I, DANIEL SEBRING, a citizen of the United States, residing at Spokane, in the county of Spokane and State of Washington, have invented certain new and useful Improvements in Saw-Gages, of which the following is a specification.

This invention relates to improvements in mortising and tenoning machines.

It is one of the objects to provide means for holding the stock together with an improved gage device, which is adjustable with respect to the supporting means for holding a saw or like tool in the desired working position with respect to the stock.

A further object is to provide an improved gage device with portions adapted to act in opposition to each other to hold an interposed tool in a predetermined position with respect to the stock and in a manner so that the held tool may be operated upon the stock.

A further object is to provide depth gaging means adapted for connection with the tool for coaction with the gage device to limit the depth of kerf or cut of the tool.

Other features and objects of the invention will be more fully described in connection with the accompanying drawings, and will be more particularly pointed out in and by the appended claims.

In the drawings:—Figure 1 is a perspective view of the device of my invention detached from its support. Fig. 2 is a sectional view taken through a portion of a bench or support, and illustrating the application thereto of the device of my invention. Fig. 3 is a plan view of the device of my invention detached from the bench. Fig. 4 is a sectional view on line 4—4 of Fig. 3. Fig. 5 is a perspective view of one form of my improved depth gage. Fig. 6 is a perspective view of a piece of stock operated on by the device of my invention.

Like characters of reference designate similar parts throughout the different figures of the drawings.

As illustrated, the device of my invention includes a stock supporting element, which may be in the form of a rectangular block 1 adapted to be disposed upon a support or bench 2. The stock supporting block 1 may be provided with a projection 3 adapted to be inserted in one of the usual bench stop holes 4, as illustrated in Fig. 2.

Another projection 5 is provided to abut against the vise face 6 of the bench and be secured by means of screws 7 for which holes 8 are provided in the projection 5. The projection 5 preferably lies flush with and forms a continuation of a stock face 9 of the block 1, and against which the stock 10 may be held by means such as a vise jaw 11.

The block 1 may be grooved, as at 12, for slidably supporting a guide 13 of a tool gage which may comprise a tool block 14, formed integral with guide 13. Guide 13 is shown provided with a slot 15 for projection therethrough of a screw 16, the latter having a head 17 in the form of a winged nut, whereby the screw 16 may be readily turned to anchor the tool gage in adjusted positions on the stock block. I prefer to recess the block 1, as indicated at 18, to form a shoulder 19, which is so disposed as to arrest adjustment of the tool gage in a direction away from the stock 10 when the tool engaging face 20 is flush with the stock engaging face 9.

A tool, which is shown in the form of a saw 21, is adapted to be disposed abreast of the tool or saw engaging face 20, whereby the saw is gaged with relation to the stock 10 so as to kerf the latter in accordance with the adjustment of the block 14 with respect to block 1. The gage block 14 is provided with a depth gaging face 22, the purpose of which will presently appear.

In order to hold the saw 21 against the block 14 and to permit of working movement of the saw 21, I provide a retaining element 23 which acts in opposition to block 14 to support the saw in working position in desired relation with the stock. The retaining element 23 is shown to be spring-actuated, and I have illustrated U-shaped strip springs 24, the ends 25 of which are shown secured to block 14 while the ends 26 are secured to retaining element 23 to not only support the latter but force it toward block 14. Retaining element 23 is mounted in a manner to dispose its upper face 27 in flush relation with gage face 22, as will be seen by reference to Fig. 2.

From the foregoing description it will be seen that the stock 28 may be kerfed at 29 and 30 to form a mortise of any desired form. If it is desired to form a tenon, then a transverse cut will be made at 31.

I will next describe my improved means

for limiting the depth of cut of the saw, so that each kerf may be made of the same depth or of selected predetermined depths.

Referring to Fig. 5, my improved depth gage is shown as comprising clamping bars 32, which are adapted to be disposed on opposite sides of the saw 21, as indicated in Fig. 2, after desired position above the depth gage faces 22 and 23. U-shaped actuating elements are provided, as indicated at 33, and the free ends thereof are connected with the bars 32, as indicated at 34. Clamping screws 35 are provided to cause the bars 32 to tightly grip the saw 21 so that when the latter has kerfed to the desired depth, the bars 32 will engage the depth gaging faces 22 and 23 and thereby prevent the saw from cutting beyond a predetermined depth.

It is believed that the advantages and utility of this invention will be clear from the foregoing description, and while I have herein shown and described one specific form of my invention, I do not wish to be limited thereto except for such limitations as the claims may import.

I claim:

1. In a saw gage, a stock supporting block having a substantially vertically disposed side face against which the stock is adapted to be engaged and also provided with a top horizontal face having a groove extending at right angles to the plane of said side face, a saw gage block adjustable in said groove and having a laterally disposed saw gage

face adapted to be shifted with said block into flush relation with said stock face or in parallel relation therewith, saw retaining strip, and U-shaped springs having their ends fixed to said gage block and retaining strip to engage the latter against the saw and hold the saw against said block, substantially as described.

2. In a saw gage, a stock block having a side face for supporting the stock with one edge of the stock flush or below the top face of said block, and a saw gage block adjustable on the top face of said stock block and having a saw gage face adapted to be disposed flush with said stock face or in overhanging relation therewith, substantially as described.

3. In a saw gage, a stock supporting block having a stock supporting face, a saw gage block adjustable on said supporting block and having a saw gage face adapted to be disposed in parallel or flush relation with said stock supporting face in accordance with the adjustment of said gage block, and a spring controlled saw retaining strip for engaging the latter against the saw to hold the saw against said saw gage face, substantially as described.

In testimony whereof I affix my signature in presence of two witnesses.

DANIEL SEBRING.
